UNITED STATES PATENT OFFICE.

WILLIAM FORGIE, OF WASHINGTON, PENNSYLVANIA.

OIL-WELL RIG.

SPECIFICATION forming part of Letters Patent No. 371,573, dated October 18, 1887.

Application filed December 16, 1886. Serial No. 221,807. (No model.)

To all whom it may concern:

Be it known that I, WILLIAM FORGIE, a citizen of Canada, residing at Washington, in the county of Washington and State of Pennsylvania, have invented certain new and useful Improvements in Oil-Well Rigs; and I do hereby declare the following to be a full, clear, and exact description of the invention, such as will enable others skilled in the art to which it pertains to make and use the same, reference being had to the accompanying drawings, which form a part of this specification.

My invention relates to an improvement in oil-well rigs, the object being to provide a means for operating the sand-reel, and also to provide a simple and durable means of connecting the crank to the walking-beam; and with these ends in view my invention consists in certain details of construction and combination of parts, as will be fully set forth hereinafter.

In the accompanying drawings, Figure 1 is a side elevation of an oil-well rig constructed in accordance with my invention. Fig. 2 is a plan view of the same. Fig. 3 is an enlarged sectional plan view of a portion of the gearing, showing a new and improved method of operating the sand-reel. Fig. 4 is an enlarged view of a device for attaching the connecting-rod to the walking-beam. Fig. 5 is a sectional view showing the manner of connecting the walking-beam to the vertical standards.

To put my invention into practice with an oil-well rig, such as I have shown at Figs. 1 and 2 of the drawings, I provide a friction-clutch consisting of two conical sections, *a* and *b*. The one *b*, I attach to the fly-wheel *J*, keyed on shaft *c*, and the other to a belt-wheel, *e*. This belt-wheel *e*, I connect by means of a belt, *w*, to another, *d*, secured to a shaft, *m*, in suitable bearings, *n*, carrying a reel, *f*. Attached to the belt-wheel *e* are a system of levers, *g*, connected to a rod, *h*, which

leads to a lever placed within easy reach of the operator while drilling. By moving this rod *h* back or forward the clutch is engaged or released at will, as will be fully described hereinafter.

To the lower end of the connecting rod *i*, I arrange a sliding block, *j*, operated by a bolt, *p*, and crank-nut *k*, whereby the journal *L* may be attached or disengaged easily from the crank *l*.

When it is desired to operate the sand-reel *f*, the rod *h*, by means of a lever, is drawn toward the well, which action, by means of the levers *g g'*, moves the belt-wheel *e* endwise on its shaft *c*, and by means of the impingement of the clutching portions *a b* engages the belt-wheel with said shaft *c*, thereby giving rotation to this wheel.

One of the levers *g* has its fulcrum at *t* (see Fig. 2) on the horizontal frame, and one end of this lever receives freely through it the shaft *c*, and is connected by loose bands *v* to the hub of the wheel *e*. The other end of said lever *g* is jointed to toggle-levers *g g'*, to the joint *s* of which the rod *h* is suitably pivoted.

Having thus described my invention, what I claim, and desire to secure by Letters Patent, is—

In an oil-well rig, the combination, with a suitable frame, of the shaft *c*, provided with a crank-arm on one end for vibrating a walking-beam, the fly-wheel *J*, keyed on shaft *c*, conical clutches *a b*, the belt-wheel *e*, loose on shaft *c*, its belt and sand-reel *f*, the lever *g* and its loose connections with the belt-wheel, the toggle levers *g'*, and the rod *h*, all constructed and adapted to operate substantially as and for the purpose described.

WILLIAM FORGIE.

Witnesses:

H. F. MORRIS,
M. E. HARRISON.
